GUSTAV AUSLANDER, OF NEW YORK, N. Y., ASSIGNOR TO PROGRESSIVE LEATHER GOODS COMPANY, A CORPORATION OF NEW YORK.

BAG-HANDLE AND BRACELET.

No. 896,264.

Specification of Letters Patent. Patented Aug. 18, 1908.

Application filed November 6, 1907. Serial No. 401,038.

To all whom it may concern:

Be it known that I, GUSTAV AUSLANDER, a subject of the Emperor of Austria-Hungary, residing at the city of New York, in the 5 county of New York and State of New York, have invented certain new and useful Improvements in Bag-Handles and Bracelets, of which the following is a specification.

My invention relates to detachable bag 10 handles which can be used as bracelets and my object is to provide such combined bag handles and bracelets with means for receiving and retaining watches. I attain this in 15 the manner shown in the accompanying drawing in which

Figure 1 is a view of my improved 1 on a bag; Fig. 2 a view of my handle 5 detached for use as a bracelet; and Fig. 3 a sectional view of the watch holding pocket.

20 Any suitable bag 1 is provided with means 2, 2' for detachably securing a handle band 3 thereto, the securing means shown comprising buckles, one of which is attached to the bag and the other to the handle band. At 25 the middle portion of the handle band a piece of material is attached to form a pocket 5 adapted to receive a watch 6. The handle band proper is provided with an aperture 7 through which the face of the watch can be 30 seen.

To prevent the accidental displacement of the watch two straps 8, 8' are secured to the handle band and carried over the open end of the pocket, partially closing it, the free ends 35 of the strap being fastened to the handle band by catches 9, 9'.

In use as a bag handle the watch carrying band is fastened to the bag as shown in Fig. 1 and when used as a bracelet it is detached 40 and the ends fastened together as shown in Fig. 2.

I claim:

1. In a hand bag, the combination of a bag body; a handle comprising a band; means for detachably securing it to the body, said means also being adapted to secure the ends of the band together when detached; and means for detachably securing a watch to said handle. 45

2. In a hand bag the combination of a bag body; a handle comprising a band with an apertured pocket therein adapted to receive a watch; means for detachably securing the handle to the bag, said means being also adapted to secure the ends of the band together when detached from the bag. 50

3. In a hand bag the combination of a bag body; a handle comprising a band with an apertured pocket therein adapted to receive a watch; means for partially closing said pocket; means for detachably securing the handle to the bag, said means being also adapted to secure the ends of the handle together when removed from the bag. 60

4. In a hand bag the combination of a bag body; a handle comprising a band provided with an apertured pocket adapted to receive a watch; straps secured to the band adjacent to the pocket and adapted to partially close the same; means for securing the free ends of the straps to the band; and means for detachably securing the handle to the bag, said means being also adapted to secure the ends of the handle together when detached. 65

In testimony whereof I, have affixed my 70 signature in presence of two witnesses.

GUSTAV AUSLANDER.
